CLAIM

The ornamental design for a fishing boat pontoon, as shown and described.

DESCRIPTION

FIG. 1 is a perspective view taken from above the right front of the pontoon as part of a fishing boat, with a seat structure and feet rest of the boat shown in phantom for illustrative purposes only and forming no part of the claimed design; FIG. 2, a perspective view taken from above the right front of the pontoon;

FIG. 3, a top plan view;

FIG. 4, a left side elevation view, the right side elevation view being a mirror image thereof;

FIG. 5, a bottom plan view;

FIG. 6, a front elevation view; and,

FIG. 7, a rear elevation view.
